ATTORNEY.

UNITED STATES PATENT OFFICE.

DAVID M. MONTGOMERY, OF FLEETWOOD, PENNSYLVANIA.

SEAM FOR BALL-COVERS, &c.

No. 857,294.

Specification of Letters Patent.

Patented June 18, 1907.

Application filed April 24, 1906. Serial No. 313,372.

To all whom it may concern:

Be it known that I, DAVID M. MONTGOMERY, a citizen of the United States, and a resident of Fleetwood, in the county of Berks, State of Pennsylvania, have invented certain new and useful Improvements in Seams for Ball-Covers, &c., of which the following is a specification.

My invention relates to an improved seam 10 adapted particularly for use in uniting the cover sections of base balls.

The main objects are first, to provide a ball having uniting stitches in connection with reinforcing longitudinal stitches running 15 parallel with the abutted edges of the cover sections and engaged by the cross-wise uniting stitches so as to avoid tearing-out of the latter; and second, to provide exposed 20 stitches upon the surface of the ball so as to enable a firmer grip of the same without incurring the liability of breaking the seam by exposing the uniting stitches as heretofore.

The invention is fully described in connection with the accompanying drawings and the 25 novel features are specifically pointed out in the claims.

Figure 1 is an exterior view of a ball, the cover-sections of which are united by my improved seam. Fig. 2 is a separate view of 30 one of the cover-sections showing the longitudinal reinforcing stitches running parallel with the edge thereof. Fig. 3 is an enlarged cross-sectional view showing the seam. Fig. 35 4 is a similar view to Fig. 3 showing a modification.

My invention relates primarily to improvements in the "game-ball" shown in Patent No. 289,297, issued November 27, 1883, to W. B. Melot, which patent provides 40 for a cover seam having uniting stitches below the exterior surface. Though the present invention is obviously applicable to other uses, it is here shown and described as applied to a game ball in which each of the several 45 features may be advantageously used.

A and B represent the usual similar cover sections of a base-ball formed of leather or suitable fabric. In covering the ball the edges of these sections are closely abutted, as 50 shown in the drawing, by means of concealed uniting stitches 2 in the manner described in the Melot patent above referred to. In my improved seam construction however these uniting stitches are practically secured 55 against pulling-out from the engaged fabric,

by means of interlocking lines of reinforcing stitches 3 extending parallel with the each abutting edge of fabric so that in the uniting operation the cross-stitches are passed through the fabric inside of the line of reinforcing stitches as indicated, so that any strains to which the uniting stitches are subjected are very effectively distributed to the fabric. These reinforcing stitches 3 may be also utilized to secure a reinforcing strip of 60 material 4, to the inner surface of each of the sections A and B, adjacent the edge thereof, as indicated in Fig. 3, thus enabling the use of a thinner cover material without undue 65 weakness at the uniting edges; or such reinforcing strips 4 may be omitted, as indicated in Fig. 4. A further object is attained by employing the reinforcing stitches 3 in the manner shown, in covering a ball. In using concealed uniting stitches, as in Melot, while 70 the stitches are thus effectually protected from the wear and tear incident to exposure, an objectionable feature has been the unusual smoothness of surface resulting from 75 locating the stitching below the surface. In my improved seam, the reinforcing stitching 80 3 being exposed exteriorly as shown, this objectionable smoothness of surface is avoided and a more secure gripping of the ball provided for, while at the same time the wear 85 and tear to which this stitching is subjected has practically no effect upon the strength of the seam.

As previously stated my invention may be otherwise applied than above specifically described and shown.

What I claim is:—

1. A ball having a sectional cover provided with lines of longitudinal stitching adjacent to the abutted edges, said edges being united 95 by cross-stitching below the exterior surface and engaging said longitudinal stitching.

2. A ball having a sectional cover provided with lines of longitudinal stitching adjacent to the abutted edges, said edges being united 100 by cross-stitching engaging said longitudinal stitching.

3. A ball having a sectional cover the abutted edges of which are provided with lines of exposed longitudinal stitching and 105 united by concealed cross-stitching engaging said longitudinal stitching.

4. A ball having a sectional cover the edge portions of which have thickening strips secured thereto by lines of longitudinal stitch- 110

ing and the abutted edges of which are united by cross-stitching engaging said longitudinal stitching.

5. A seam composed of abutting fabric edges each having a parallel line of reinforcing stitches, and uniting stitching engaging both lines of reinforcing stitches.

6. A seam composed of abutting fabric edges each having a parallel line of reinforcing stitches, and uniting stitches below one surface of the fabric and engaging both lines of reinforcing stitches.

7. A seam composed of abutting fabric edges each having a reinforcing strip on one face thereof and a parallel line of reinforcing

stitches, and uniting stitches engaging both lines of reinforcing stitches.

8. A seam composed of abutting fabric edges each having a reinforcing strip on one face thereof and a parallel line of reinforcing 20 stitches, and uniting stitches below one surface of the fabric and engaging both lines of reinforcing stitches.

In testimony whereof, I affix my signature in the presence of two witnesses.

DAVID M. MONTGOMERY.
